[57] CLAIM

The ornamental design for a fluorescent lighting fixture, as shown and described.

DESCRIPTION

FIG. 1 is a bottom, end and side perspective view of a fluorescent lighting fixture showing my new design;

FIG. 2 is a bottom plan view thereof;

FIG. 3 is a top plan view thereof;

FIG. 4 is an elevational view thereof taken from the side opposite that shown in FIG. 1; and

FIG. 5 is an elevational view thereof taken from the end opposite that shown in FIG. 1.
